DROP BOTTOM CONTAINER HAVING LATCH
MEANS THEREFOR

Carl E. Johansson, Cleveland, Ohio, assignor to The Youngstown Steel Door Company, Cleveland, Ohio, a corporation of Ohio

Filed Feb. 27, 1963, Ser. No. 261,377
10 Claims. (Cl. 214—1)

This invention relates to containers for transporting bulk materials, and more particularly to containers of the drop bottom type.

Containers of the general class herein illustrated are designed to function as receptacles for bulk material during transportation of the material from one point to another. Transportation of the material is usually effected by means of trucks transporting the loaded containers to and from a railroad terminal. Upon reaching the destination point, the containers are removed from the trucks or railroad cars either by cranes or fork lift trucks with the cranes or fork lift trucks being used to maneuver the loaded containers to the appropriate position where the material carried by the containers is to be used. Upon attaining this position, the trip mechanism for the drop bottom container is actuated and the material is deposited.

In the conventional drop bottom containers actuation of the trip mechanism has required that an additional man be present other than the crane operator or fork lift truck operator so as to be available to actuate the tripping mechanism to dump the contents of the container. Alternatively, the operator of the crane or fork lift truck was required to dismount and operate the trip mechanism for the drop bottom container and then remount the machine to remove the container. Such an arrangement has occasioned considerable inconvenience. This inconvenience is multiplied when a container with multiple sections and doors is utilized. With a multiple section container, the usual approach has been to provide a single tripping mechanism for each section, thus requiring the operator to empty each section of the container individually.

It is an object of this invention to provide a drop bottom container that is convenient to operate.

It is a further object of this invention to provide a container that provides a latch tripping mechanism designed to be easily accessible to either a fork lift truck operator or a crane operator.

It is a still further object of this invention to provide a latch tripping mechanism for a drop bottom container that may be utilized to simultaneously empty all sections of a multi-section container.

It is another object of this invention to provide a drop bottom container that includes a latch tripping mechanism having release actuating means remote from the latch location.

It is a further object of this invention to provide a drop bottom container with hinged bottom discharge doors having a latch mechanism releasably maintaining the doors in closed position and a release device remote from said latch mechanism, but operatively connected thereto.

It is a still further object of this invention to provide a drop bottom container having hinged bottom discharge doors with a latch maintaining said doors in closed position and a spring bias release cable operatively connected by a shaft to the latch mechanism for operation of the same.

The embodiment of the invention illustrated herein may be utilized in drop bottom containers of diverse configurations. The preferred embodiment includes a latch pivoted on the container and engaging the free edge of

2

a hinged bottom closure to retain the closure in closed position. A shaft is rotatably mounted in the container and includes a crank carrying a roller operatively engaging a roller on the latch. A spring biased release cable is secured at one end to the shaft with the other end of the cable accessible from the exterior of the container. Upon actuation of the release cable, the shaft is rotated causing rotation of the crank to release the latch and allow the weight of the material in the container to pivot the latch and release the bottom closure.

To the accomplishment of the foregoing and related ends the following description sets forth in detail selected embodiments of the invention. Such disclosed means are not meant to be limiting, being but a few of the various ways in which the principles of the invention may be used.

In the drawings:

FIG. 1 is a prospective view of a suitable container wherein the invention may be utilized;

FIG. 2 illustrates in fragmentary plan view one of the lifting hook means illustrated in FIG. 1;

FIG. 3 is a partial side elevation, partly in section, of the lower portion of the container illustrating the instant invention;

FIG. 4 is a view taken along line 4—4 of FIG. 3;

FIG. 5 is a partial end elevation, partly in section, showing the instant invention;

FIG. 6 is a view taken along line 6—6 of FIG. 3;

FIG. 7 is a view taken along line 7—7 of FIG. 3;

FIG. 8 illustrates the invention utilized in a different type of drop bottom container;

FIG. 9 is a partial end elevation showing, partly in section, a second embodiment of the invention;

FIG. 10 is a plan view of FIG. 9; and

FIG. 11 is a partial side elevation of the embodiment of FIG. 9.

Turning to FIG. 1, the reference numeral 10 indicates generally one type of container in which the invention may be utilized. It should be understood that the particular configuration of the container is immaterial so long as a hinged bottom closure is being utilized. The container 10 includes side walls 11 and 12 and end walls 13 and 14, with each of these walls terminating at a point above the bottom of the container. Corner angle members 15, 16, 17 and 18 secure adjacent marginal edges of the walls by means of rivets 19 or the like. Lifting hooks 20 are provided at each corner.

The base of the container is formed by side and end angles 21, 22, 23 and 24, with the ends of each angle being secured to the corner angles. At the lower terminus of each of the side and end walls there is provided structure comprising a discharge hopper. The discharge hopper comprises inwardly directed slope sheets 25, 26, 27 and 28 connected to the side and end walls 11, 12, 13 and 14, respectively. As may be viewed in FIG. 7, each of the slope sheets are secured by rivets 29 to the lower terminal portion of its associated wall and includes a depending vertical portion 30, 31, 32 and 33 defining a rectangular discharge opening.

The rectangular opening formed by the depending legs of the slope sheets is adapted to be closed by a conventional hinged door. As shown in FIG. 5, the door 34 is pivotally received on pins 35 carried by the container. At the side of the door, opposite to the hinges, there is provided a pair of identical latch mechanisms indicated generally by the reference numerals 36a and 36b. Each of the latch mechanisms are of the general configuration as that shown in my prior U.S. Patent No. 2,697,002, issued on December 14, 1954.

Adjacent to the slope sheet 25 and acting as reinforcements therefor are plates 37, 38 and 39, 40. Each of the

plates are secured to the slope sheet and the base angle 21 and provide a housing for one of the latch mechanisms. A cover plate 41 is associated with the housing formed by plates 37 and 38 and a cover plate 42 is associated with the plates 39 and 40.

Referring to FIG. 7, wherein one of the latch mechanisms is shown more in detail, the latch comprises a hook shaped member 43. The hook shaped member 43 includes spaced apart jaws 44 and 45, with the lower jaw 44 functioning to support the door 34 in closed position. The latch 43 is pivotally mounted on a pin 46 carried by the associated plates 37 and 38. A bushing 47 is interposed between the pin 46 and the latch 43.

At the upper end of the latch is formed a fork portion 48 of the latch receiving a pin 49. On the pin 49 is received a roller 50 with a bushing interposed between the pin and the roller. A second roller is carried by the latch on a fork portion of the upper jaw 45 wherein a pin 51 rotatably receives the roller 52. It is believed apparent, as shown in FIG. 7, that with the door in closed position and the lower jaw 44 of the latch 43 supporting the door, the weight of the material in the container will exert a force downward on the door which in turn will tend to rotate the latch in a clockwise direction around pin 46.

Turning now to FIG. 4, there are illustrated means for controlling the tendency of the latches to rotate and release the door closure. The controlling means comprises a shaft 53 having one end journalled in a bearing 54 in the plate 37, with the other end of the shaft journalled in a bearing 55 in the side angle 16. A second shaft 56 is journalled at one end in a bearing 57 in the side plate 38 and at the other end in a bearing 58 in the plate 39. A third short stub shaft 59 is journalled in the plate 40. The adjacent ends of shafts 56 and 59 function in an identical manner so only one latch mechanism, 36a will be discussed in detail.

Mounted on adjacent ends of the shafts 53 and 56 are crank arms 60 and 61, respectively. The crank arms are secured by pins 62 for rotation with the shafts 53 and 56. The configuration of the crank arms 60 and 61 is such that they are situated contiguous to the roller 50. A pin 62a interconnects the two crank arms 60 and 61 with a roller 63 journalled on the pin. Due to the relationship of the crank arms 60 and 61 and the diameter of the roller 63, the roller 63 is in rolling engagement with the roller 50 carried by the latch 43. This is clearly illustrated in FIG. 7. It may be seen that with the crank arms in the position shown in FIG. 7, the roller 63 abuts the roller 50 and serves as a means for restraining the clockwise rotation of the latch 43 to thereby retain the bottom closure in closed position.

In order to empty the container, it is necessary to remove the roller 63 from the position shown in FIG. 7 so that the door is free to pivot the latch 43 to a position where it no longer restrains the opening of the door. This is accomplished by means of a spring biased release mechanism. The release mechanism comprises a segmental drum or actuating arm 64 secured to the shaft 53. Attached to the segmental drum by a bolt 65 is a flexible cable 66. The cable extends around the periphery of the drum and has at the end opposite to the bolt-connected end a pull ring 67. The pull ring 67 is received in a cup shaped member 68 which is secured to the side angle 16 and is easily accessible for operation of the release mechanism.

It is believed obvious that upon pulling movement on the pull ring 67 the segmental drum 64 will be rotated, causing rotation of the shaft 53. This rotation of the shaft 53 will in turn cause rotation of the crank arms 60 and 61 and the second shaft 56.

A biasing force in the form of a helical spring 69 is attached at one end thereof by means of a pin 70 to the segmental drum 64 so that upon release of the pull ring 67 the spring 69 will automatically return the segmental

drum to its original position. The other end of the helical spring is secured to a pin 71 carried on a plate 72 secured to the container. As a means of limiting the return biasing effect of the spring 69, an angle 73 is secured to the side wall 14 and the plate 72 and is so positioned to cooperate with a flange portion 74 on the segmental drum 64.

By virtue of the latch and release mechanism shown, the container would be used in the following manner. Assuming the container is filled with material, the material would exert a force downward on the bottom closure 34 which in turn would act through jaw 44 on the latch 43 tending to rotate the latch 43 in a clockwise direction. However, the helical spring 69 has biased the drum 64 to a position wherein the shaft 53 is rotated such that the roller 63 is positioned to restrain this clockwise movement. A fork lift truck operator would then transport the loaded container to the position wherein the material is to be utilized. Upon reaching this position, the operator of the fork lift truck may reach forward to the edge of the container and operate the pull ring 67 to dump the contents of the container. With the previous arrangement of the pull ring positioned directly over the latch, it was necessary for the fork lift operator to dismount or a second person to operate the pull ring inasmuch as the pull ring was inaccessible to an operator seated on the vehicle.

Upon pulling the pull ring 54 to the position shown in dotted lines in FIG. 6, the segmental drum 64 will be rotated against the spring bias of the helical spring 69 thereby rotating the shaft 53. Rotation of the shaft 53 will also rotate the crank arms 60 and 61 and the additional shaft 56, which in turn will cause rotation of the crank arms associated with the second release mechanism 36b. Rotation of the crank arms 60 and 61 will cause the roller 63 to roll around the periphery of the roller 50, that is, in a counterclockwise direction, as viewed in FIG. 7. When the roller 63 has reached a point vertically above the pin 46 the restraining force of the roller 63 on the clockwise movement of the latch 43 will then be removed. Due to the force of the material in the container exerted on the door 34 the latch 43 will be pivoted in a clockwise direction and the door 34 will be pivoted about the pin 35 thereby emptying the contents of the container. To cushion the movement of the door in the opening operation, a cushioning member 75 is secured to the door 34 and adapted to co-operate with a bevelled surface 76 on the frame of the container.

Upon release of the door, the operator is free to release the pull ring 67 whereupon the helical spring 69 will return the pull ring, segmental drum 64, shaft 53 and associated parts to their initial position. The angle 73 will co-operate with the flange 74 to limit the return movement under the bias of the spring 69. As the shaft 53 is rotated back to its initial position, the crank arms will cause the roller 63 to attempt to return to its initial position; however, the latch 43 is now in a position pivoted clockwise from the position shown in FIG. 7 and the roller 63 will be restrained by roller 50 from returning to its position.

Upon lowering of the container to the floor, the door 34 will be pivoted back to a closing position. As it is being pivoted to this position, the upper surface of the door will engage the roller 52 on the latch 43 and cause the latch 43 to be pivoted in a counterclockwise direction. This is shown in dotted lines in FIG. 6. As the latch 43 is being pivoted counterclockwise, the roller 63 will roll over the periphery of the roller 50 causing pivoting movement of the crank arms 60 and 61, and the shafts as well, against the bias of the spring 69. When the door reaches the closing position, the latch 43 will be in a substantially vertical position and the bias of the spring 69 will have caused the roller 63 to return to the position shown in FIG. 7.

It may be seen that by placing the spring release mechanism at one corner of the container, greater convenience

is effected. Also, through utilization of a shaft to connect the release mechanism to the latch, it is possible to then couple several latches in series, all being operated from the same release mechanism. The simultaneous actuation of a series of latches is particularly advantageous in the container illustrated in FIG. 8. In this container separate bins 77 and 78 are provided, each having a separate discharge opening 79 and 80. Using two latch mechanisms per door closure, it is obvious that each of these latches is much more preferable than an individual release mechanism for each latch.

Turning to the embodiment of the invention illustrated in FIGS. 9 to 11, there is disclosed a container 81 which is comparable to the container 10 shown in FIG. 1, but of a slightly different configuration. The container 81 includes lifting hooks 82 and a frame construction similar to the previously described containers. A door closure 83 and a latch and release mechanism similar to that shown in my prior Patent No. 2,697,002 is also used. Thus, the release mechanism 84 is directly associated with the latch device 85, as may be viewed in FIG. 11.

Modifying this basic structure, however, there has been added a shaft 86 having one end coupled to the conventional pull ring release mechanism 84, with the other end of the shaft journaled at 87 on the corner angle. Secured to the shaft 86 is a segmental drum 88 to which is attached a flexible cable 89. The cable 89 is passed around a guide 90 carried on the frame of the container and passes through a channel member 91. The channel member is secured vertically to the side of the container and is in communication with an opening 92 in the top apron of the container. A pull ring 93 is secured to the end of the cable 89.

With the arrangement shown in FIG. 9, either of the pull rings 84 or 93 may be actuated, depending upon the location of the operator of the transporting vehicle. Thus, the conventional pull ring 84 may be operated to release the latch 85 and dump the contents of the container, or the pull ring 93 may be actuated in which case the segmental drum 88 would be rotated in a direction rotating the shaft 86, which in turn would, in a manner described above, release the latch.

It should be understood that the precise location of the pull ring is immaterial and dependent solely upon the position that is most convenient for the operator. Thus, the pull ring might be positioned on the side of the container, as well as the top or on the side angle, and, in fact, might be positioned below the container if this were conveniently necessary. Also, pull rings both at the top and at a side angle might be utilized.

It is not my intention that the illustrated embodiments, nor the terminology employed in describing them, be limiting inasmuch as variations in these may be made without departing from the spirit of the invention, but rather are desired to be restricted only by the scope of the appended claims.

I claim:

1. A transportation container for bulk materials having a discharge opening in the bottom thereof, 60 a hinged door adapted to close the discharge opening, a substantially hook shape latch member for said door pivotally mounted on said container, the hook portion of said latch member being adapted to engage the underside of the swing end of said door, 65 a roller at the upper end of said latch member, shaft means rotatably mounted on said container, crank means carried by said shaft means for rotation therewith, 70 a roller on said crank means engageable with said roller on said latch member for maintaining the latter in latching engagement with said door, a segmental drum secured to said shaft means at an end remote from said crank means, 75

biasing means fastened to said drum and said container, and

manually operable means fastened to said drum for imparting rotation thereto, against the action of said spring, whereby the roller on said crank means rolls over the roller on said latch member to allow pivoting movement of said latch member and permit opening movement of said door.

2. A container for bulk materials having a discharge opening in the bottom thereof, a door hingedly carried on said container and adapted to close the discharge opening,

latching means pivotally mounted on said container, said latching means being adapted to maintain said door in a position closing the discharge opening, shaft means rotatably mounted on said container, roller means carried by said shaft means and being operable to retain said latch means in latching engagement with said door,

latch releasing mechanism remote from said latch means and being operatively connected to said shaft means for controlling said roller means, said latch releasing mechanism including, manually operable means for rotating said shaft thereby to release said latch means and permit opening movement of said door.

3. A container for bulk materials having a discharge opening in the bottom thereof,

a hinged door adapted to close the discharge opening, latch means pivotally mounted on said container and adapted to retain said door in closed position, said latch means being movable between a latching position and a door releasing position,

shaft means rotatably mounted on said container, roller means carried by said shaft means in engagement with said latch means to retain the latter in latching position,

latch releasing mechanism associated with said shaft remote from said roller means and including, manually operable means for imparting rotation to said shaft means to thereby move said roller means relative to said latch means and permit said latch means to pivot to a door releasing position and spring means associated with said latch releasing mechanism operable to return said roller means to a position maintaining said latch means in a door releasing position.

4. A transportation container for bulk materials having,

a discharge opening in the bottom thereof, a door pivotally secured to said container and adapted to close the discharge opening,

latch means pivotally mounted on said container, said latch means being movable between a position latching said door in closed position and a door releasing position, shaft means extending between said latch means and one corner of said container,

a roller in abutting engagement with said latch means and secured to said shaft means for rotation therewith,

releasing mechanism attached to said shaft means at said one corner of said container,

spring means secured to said release mechanism and maintaining said shaft and said roller in a position wherein said latch means is retained in a door closing position,

manually operable means associated with said release mechanism and being operable to rotate said shaft and said roller against the bias of said spring whereby said roller is removed from the position retaining said latch means in the door closing position and to thereby permit opening movement of said door.

5. The container of claim 4 wherein there are means

mounting said manually operable means on said container at one corner thereof.

6. A transportation container for bulk materials having,
- a discharge opening in the bottom thereof,
  - a door pivotally attached to said container and adapted to close the discharge opening,
  - a latch member having a roller at one end thereof pivotally mounted on said container,
  - said latch member being movable between a door latching position and a door releasing position,
  - a latch releasing mechanism disposed in one corner of said container,
  - shaft means rotatably mounted on said container and extending between said latch releasing mechanism and said latch member,
  - crank arms secured to said shaft means,
  - roller means carried by said crank arms and being operatively associated with said latch member,
  - said latch releasing mechanism including,
  - a drum secured to said shaft means,
  - biasing means operatively associated with said drum and biasing said shaft means and said crank arms to a position wherein said roller means on said crank arms is in abutting engagement with said roller on said member,
  - manually operable flexible means secured to said drum and extending externally of said container whereby actuation of said manual means rotates said drum against the bias of said biasing means causing rotation of said shaft and crank arms, whereby said roller on said crank arms rolls over said roller on said latch means to effect release of said latch means and permit opening movement of said door.
7. In a container for bulk materials having a discharge opening in the bottom thereof;
- a door pivotally attached to said container and adapted to close the discharge opening;
  - a latch member pivotally mounted intermediate its end on the container adjacent the free edge of said door;
  - said latch member being movable between a door

latching position and a door releasing position; a roller mounted on one end of said latch member; shaft means rotatably mounted on said container with a portion of said shaft means being adjacent said latch member; said shaft means being coaxial with said roller when said latch member is in a door latching position; crank means secured to said portion of said shaft means for rotation therewith; roller means mounted on said crank means and being aligned with said roller on said latch member for rolling contact thereagainst; one end of said shaft means terminating at one corner of said container; spring means operatively associated with said shaft means and normally biasing said shaft means, crank means, and roller means to a position wherein said roller means engages said roller on said latch member; and manually operable means operatively connected with said one end of said shaft means and being operable to rotate said shaft means against the bias of said spring means.

8. The container of claim 7 wherein an access opening is provided in one corner of said container, with said manually operable means projecting through the opening.

9. The container of claim 7 which includes a vertical channel member opening upwardly of said container, with said manually operable means being received in said channel and projecting outwardly of the container.

10. The container of claim 9 and further including additional manually operable means associated with said crank means whereby said shaft means may be rotated by either of said manually operable means.
